BANK DEPOSIT BAG

Sidney B. Klahn, Portland, Oreg.

Application February 19, 1937, Serial No. 126,583

3 Claims. (Cl. 150—7)

This invention relates generally to bags for containing valuables, and particularly to a bank deposit bag.

The main object of this invention is the construction of an improved form of deposit bag which will be simple to manufacture, easy to open and close by an authorized person, but difficult to gain access thereto by an unauthorized person without showing that it has been tampered with.

The second object is to construct a bag of the character described which will be durable in construction and inexpensive to manufacture and maintain.

These and other objects are accomplished in the manner set forth in the following specification as illustrated in the accompanying drawing, in which:

Fig. 1 is a front elevation of the bag in open position.

Fig. 2 is a rear elevation of the bag.

Fig. 3 is a front elevation of the bag showing one corner flap folded to a partially closed position.

Fig. 4 is a fragmentary front elevation showing both corner flaps folded to a partially closed position.

Fig. 5 is a fragmentary elevation showing the folded flaps turned engaging the staple and the lock in position.

Fig. 6 is a side elevation showing the locked bag.

Fig. 7 is a transverse section taken along the line 7—7 in Fig. 1.

Fig. 8 is a transverse section taken along the line 8—8 in Fig. 1.

Similar numbers of reference refer to similar parts throughout the several views.

Referring in detail to the drawing, there is shown a bag consisting of the front 10 and back 11 which are joined by the seams 12 and 13. On the upper portion of the back 11 is fixed a triangular center flap 14 whose base 15 is parallel with the bottom seam 13.

Also attached to the back 11 are the corner stiffening flaps 16 which are somewhat triangular in shape and their edges 17 form a folding line with the edges 18 of the center flap 14. The edges 18 of the flaps 16 are substantially parallel with the seams 12. The edges 20 have formed thereon the projection 21 which contains the slot 22. It will be noted that the slots 22 of the two flaps 16 register when the flaps are in the position shown in Fig. 4.

On the inside of the front 10 is secured a staple base 23 to which is attached a staple 24 which

projects through the front 10. A leather hasp 25 having a slot 26 is secured to the front 10 directly below the staple 24. Directly above the base 23 is secured a stiffening plate 27 which may be of any suitable material. A slot 28 is formed through the front 10 and the plate 27 and registers with the staple 24 when the bag is in a closed position. The center flap 14 is also provided with a slot 29 which is directly opposite the slot 28.

In order to close the bag, it is first necessary to move one of the flaps 16 to the position shown in Fig. 3 and then to move the other flap 16 to the position shown in Fig. 4 and to then fold the center flap 14 downwardly over the staple 24 and then place the hasp 25 in position over the staple 24 after which a lock 30 is placed in the staple 24 or a suitable seal is substituted for the lock.

It can be seen that when the bag is closed as stated that it will be impossible to open the bag without mutilating it or opening the lock or destroying the seal.

It will be understood that the nature of this bag is to provide safe carriage for valuables against tampering only since it is obvious that if anyone desired to take the contents of the bag, it would be a very convenient way of taking them, by taking the bag itself or by cutting the canvas bag open with an ordinary knife. The bag herein described is intended only to prevent tampering with the contents as stated.

While it is desirable to make the parts 10 and 11 out of a heavy fabric and the parts 14, 16, 23, 25 and 27 out of leather, they could, of course, be made out of any other material without departing from the spirit of this invention.

I claim:

1. A device of the class described, comprising an open mouthed bag of flexible material having triangular stiffening flaps mounted in the corners of the open end, each of said flaps having a slot formed therein parallel with the open end, said flaps being adapted to fold diagonally against one side of said bag in a manner that their slots will register, said bag having a slot formed through opposite sides thereof adapted to register with the flap slots while they are in register, a staple projecting from one side of said bag adapted to extend through the flap slots and through the bag and to project therefrom and means for preventing the withdrawal of said staple from said slots said bag being rectangular in outline when closed.

2. A device of the class described comprising an open mouthed bag of flexible material having a staple base and a stiffening plate mounted on

- one side thereof, the adjacent edges of which form a folding line normal to the length of the bag, said staple plate having a staple projecting therefrom, said bag having a slotted hasp disposed adjacent to said staple, said bag and stiffening plate having slots therein adapted to register with said staple when the mouth of the bag is folded along its full width along the line between said staple plate and stiffening plate and corner stiffening flaps at the outer corners of said bag having slots therein adapted to register with said staple when said flaps are folded against said bag in a manner to make the slotted edges thereof overlap.
- 15 3. A device of the class described comprising a canvas bag having an open end having triangular corner stiffening flaps secured to the outermost corners thereof, one side of which is parallel to the open edge of the bag and another side is par-

allel to the side edge of the bag and the third side forms a diagonal line extending from the middle of the open edge to a point along a side edge, each of said flaps having a slotted projection formed thereon extending beyond the open end of the bag, a triangular center flap secured to one side of the mouth of the bag between the corner flaps, a stiffening plate mounted on the opposite end of said bag, said bag stiffening plate and center flap having slots formed therethrough adapted to register with the slots in said projections when said projections are made to overlap, a staple secured to said bag adapted to project through all of said slots, a hasp attached to said bag adapted to engage said staple and a lock 15 for the projecting end of said staple, said bag being characterized by having a rectangular shape when open or closed.

SIDNEY B. KLAHN.
